United States Patent

Des. 240,512
Patented July 13, 1976

240,512

ELECTRONIC BICYCLE SPEEDOMETER

David E. Erisman, 515 S. Maguire,
Warrensburg, Mo. 64093

Filed Oct. 15, 1974, Ser. No. 514,469

Term of patent 14 years

Int. Cl. D10—04

U.S. Cl. D10—98

Fig. 1.

Fig. 3.

Fig. 2.

Fig. 4.

Fig. 5.

FIG. 1 is a top perspective view of an electronic bicycle speedometer showing my new design;

FIG. 2 is a top plan view thereof;

FIG. 3 is a right end elevational view thereof;

FIG. 4 is a lower side elevational view thereof;

FIG. 5 is a bottom plan view thereof.

I claim:

The ornamental design for an electronic bicycle speedometer, as shown and described.
